UNITED STATES PATENT OFFICE.

FRED G. WARNER, OF NARBERTH, PENNSYLVANIA, ASSIGNOR TO WALLACE & WARNER, A PARTNERSHIP COMPOSED OF BRENTON G. WALLACE AND FRED G. WARNER, OF PHILADELPHIA, PENNSYLVANIA.

DESIGN FOR A SIGNBOARD.

Application filed July 2, 1925. Serial No. 13,981. Term of patent 14 years.

To all whom it may concern:

Be it known that I, FRED G. WARNER, a citizen of the United States, residing at Narberth, in the county of Montgomery and State of Pennsylvania, have invented a new, original, and ornamental Design for Signboard, of which the following is a specification, reference being had to the accompanying drawing, forming part thereof.

The figure is a perspective view of a signboard showing my new design.

I claim:

The ornamental design for a signboard, as shown.

In testimony whereof, I have hereunto signed my name.

FRED G. WARNER.
